Pennsylvania Stockings Corp. ATTORNEYS.

UNITED STATES PATENT OFFICE.

JACOB H. WEBER, OF BROOKLYN, NEW YORK.

SOUND BOX.

1,409,503.

Specification of Letters Patent. Patented Mar. 14, 1922.

Application filed December 8, 1920. Serial No. 429,061.

To all whom it may concern:

Be it known that I, JACOB H. WEBER, a citizen of the United States, residing at Brooklyn, in the county of Kings and State 5 of New York, have invented certain new and useful Improvements in Sound Boxes, of which the following is a full, clear, and exact description.

This invention relates to sound boxes and 10 particularly to stylus bar mountings having knife edge bearings. I have found that the oscillations of the stylus bar upon the knife edge bearings will in a short time wear off the sharp edges leaving blunt bearing surfaces which do not provide the same freedom 15 of movement as the knife edges and the reproduction or recordation as a result is faulty and unsatisfactory. The wearing off of the knife edges permits a movement of the 20 stylus bar toward the center of the casing which either buckles the diaphragm or shifts it in its plane to displace the point of attachment between the bar and the diaphragm eccentrically of the sound wave outlet of 25 the casing. The effect upon the sound emitted by the box in either case is very unsatisfactory and displeasing. If the bearing edges are sharpened a number of times the displacement of the stylus bar is increased 30 and the faulty and unsatisfactory effect upon the sound waves amplified, so that after a few sharpenings the box must be discarded or some correction provided. Where the 35 knife edges are integral with the casing, the material is soft and wears quickly, and in order to overcome the above objections the whole box is discarded after a few sharpenings of the edges. Where the bearings are provided on removable plates or elements 40 attached to the box or stylus bar by screws or screw threads it has been found that the vibrations of the stylus bar soon cause a loosening of the screws and plates and as a result chattering and other objectionable 45 sounds.

An object of my invention is to provide a stylus bar mounting for sound boxes having readily renewable bearings which can be of various desired materials, or of various 50 degrees of hardness, and in which the bearings are secured to the casing or stylus bar in a manner to eliminate danger of loosening or chattering, in the use of the box, of any of the elements of the mounting. A further 55 object is to provide a mounting of this type and for this purpose which is simple and

inexpensive and in which the bearings can be replaced at a very low cost and by inexperienced persons. Other objects and advantages will be apparent from the following description and the novel features of the invention will be particularly pointed out in the claim. 60

In carrying my invention into practice, I provide either the casing or the stylus bar 65 with a slot or socket in which is disposed a removable and replaceable bearing element. Springs upon the casing press the stylus bar toward the casing with the bearing element between and form the sole means for preventing their separation and for holding the bearing element in its slot or socket. The bearing element is preferably a bar or strip with spaced knife edges or points thereon which provide the bearing points or lines. 75 By the release of the stylus bar from the springs the bearing bar can be removed, a new one can be inserted in the slot or socket, and the springs made effective again to hold the bearing bar within its slot. 80

In the accompanying drawing:

Fig. 1 is a front elevation of a sound box constructed in accordance with my invention.

Fig. 2 is a bottom plan of the same.

Fig. 3 is a side elevation of the same.

Fig. 4 is a bottom plan of the same with the stylus bar and securing springs removed, and

Fig. 5 is a perspective of the removable 90 bearing element.

In the illustrated embodiment the casing 1 is provided with a flat surface 2 upon one portion of its periphery. Extending inwardly from this surface in a direction parallel to the diaphragm is a slot 3 in which is removably disposed a blade-like bearing element 4 having upon its outer edge a pair of spaced knife edges 4^a or points which act as bearings for the stylus bar 5. The stylus bar has a flat surface with a slight depression, which abuts against the knife edges or points, the stylus bar being held against the same with the knife edges in the depressions by flat spring strips 7 which are secured at 95 one end by screws 8 to lugs 9 of the casing and bear at their free ends upon the stylus bar to hold it yieldingly against the bearing edges. The lugs 9 are disposed on the casing upon opposite sides of the knife edges, 110 and each of the spring strips extends across the bar and bears upon the side of the bar

furthest from its lug, so as to have a maximum resiliency. The spring strips by bearing upon the stylus bar on opposite sides of the line of contact of the knife edges with the stylus bar tend to return the stylus bar to a normal central position when displaced therefrom in rocking upon the knife edges. Pads 10 of rubber, felt or similar sound insulating material are interposed between the free ends of the spring strips and the stylus bar so as to prevent the transmission of needle vibrations from the stylus bar through the spring strips directly to the casing. Such vibrations may be caused for example by roughness in the surfaces of the record grooves and if permitted to pass directly to the casing and set the latter in vibration they cause the addition to the sound waves set up by the diaphragm of a very displeasing sound. The pressure of the spring upon the stylus bar holds the latter yieldingly against the knife edges thus forming the sole attaching or securing means between them, and also holds the bearing element carrying the knife edges within its slot. The spring strips therefore have a triple function, viz: (1) securing the stylus bar operably to the casing; (2) holding the bearing element or bar 4 within its socket and (3) exerting rotative forces upon the stylus bar tending to return the same to a normal position when displaced therefrom by a rocking movement upon the knife edges.

The bearing elements 4 can be made at a very low cost by stamping or they can be formed of mineral or very hard substances such as quartz, glass, etc. If made by steel they can be case hardened or tempered. The edges 4^a wear much longer before becoming dull when made of hard substances or when they are hardened, and all that is

necessary to replace the bearing edges is to loosen the spring strips, slide the bearing bar 4 endwise out of the slot and replace another new bearing bar or element in the reverse manner, after which the spring strips can be tightened by screwing down the screws 8. In this manner it is not necessary to discard the whole box, since it can be rapidly and easily repaired at a very low cost by inexperienced persons. The stylus bar is not secured in position by any screws which will be likely to become loosened by the vibrations of the bar or box with a resultant impairment of the sound emitted by the box. I have also found that a sound box constructed in accordance with my invention reproduces sound waves from a record with exceptional detail, color and clearness but I am unable to account theoretically for this effect.

It will be understood that the embodiment herein described and illustrated is for the purpose of illustration of the principle of the invention only, and that various changes in the details and arrangement of the parts may be made within the scope of the invention.

I claim:

In a sound box, the combination of a casing having a slot therein, a bearing bar removably disposed in the slot and having spaced sharp bearing surfaces extending therefrom and away from the casing, a stylus bar, springs carried by the casing and having bearing contact upon the stylus bar to press it against the bearing surfaces of the removable bar and hold the latter within its slot.

In witness whereof, I hereunto subscribe my signature.

JACOB H. WEBER.
